COMBINED KITCHEN FAUCET AND HANDLE

James E. Niemann, Louisville, Ky., assignor to American Standard Inc., New York, N.Y., a corporation of Delaware

Filed Nov. 18, 1969, Ser. No. 20,160

Term of patent 14 years

Int. Cl. D23—01

U.S. Cl. D23—23

Fig. 1.

Fig. 2.

Fig. 3.

Fig. 4.

Fig. 5.

FIG. 1 is a side elevational view of a combined kitchen faucet and handle embodying my new design;

FIG. 2 is a top plan view thereof;

FIG. 3 is a front elevational view thereof;

FIG. 4 is another side elevational view thereof taken on the side opposite to that shown in FIG. 1; and

FIG. 5 is a perspective view thereof.

I claim:

The ornamental design for a combined kitchen faucet and handle, substantially as shown.
